UNITED STATES PATENT OFFICE

STERLING H. CAMPBELL, FREDERICK K. HABENICHT, AND FRANK H. PIETZSCH, OF ST. LOUIS, MISSOURI, ASSIGNEES TO WESTERN RAILWAY EQUIPMENT COMPANY, OF ST. LOUIS, MISSOURI, A CORPORATION OF MISSOURI

JOURNAL BEARING FOR RAILWAY CARS

Application filed January 29, 1932. Serial No. 589,636.

Journal bearings for railway cars are commonly lubricated by means of oil soaked cotton waste or similar absorbent material packed in the lower part of the journal box so as to contact with the bearing surface of the axle. It has been found that portions of the packing are carried around, by the rotation of the axle, to a point adjacent the brass and, when the bearing surfaces of the axle and brass are separated, such portions of the packing are admitted between the brass and axle forming "waste grabs", resulting in friction and heating of the bearing. The separation of the bearing surfaces of the axle and brass may be caused either by the impact of the car against another car, or by excessive application of the brakes, or by the combined effect of impact and brake pressure and is of frequent occurrence in ordinary operation of a railway train.

One object of our invention is to provide expandable fillers located at each side of the axle between the packing and the brass for maintaining a seal between the brass and the packing to prevent the formation of "waste grabs".

Another object of our invention is to so construct and position such fillers that they will not be injured by the relative movement of the axle and box.

A further object of our invention is to enable the insertion and removal of the fillers, not only with the parts of the bearing assembled, but also while the packing is in place in the box.

In the accompanying drawings Figure 1 is a top plan view, the journal box and one of the fillers being shown in section; Figure 2 is a section taken on the line 2—2 of Figure 1; Figure 3 is an enlarged cross section of one of the fillers; Figure 4 is a perspective view of one of the fillers; Figure 5 is a top plan view showing a modified form, the flexible covering of one of the fillers being partially broken away; Figure 6 is a side view of the form shown in Figure 5; Figure 7 is an end view, partly in section and partly in elevation, illustrating the application of the form shown in Figures 5 and 6; and Figures 8 and 9 are detail views showing a modifica-

tion of the handle for inserting and removing the filler.

Referring first to Figures 1 to 4, 1 indicates a journal box of standard type provided with box lugs 2 and containing the usual brass 3 and wedge 4. The lower part of the box forms a chamber containing the packing 5 of cotton waste or other absorbent material saturated with oil for lubricating the bearing of the axle 6. Situated at either side of the axle, between the packing and the brass, is one of the expandable fillers now to be described.

Each of the fillers comprises a contact strip 7, preferably of fiberboard bearing against the axle, a pair of expansion springs 8 secured to the strip, and a flexible cover. The springs may be secured to the strip 7 by means of clips 9 fastened by rivets 10 which also secure to the strip a tape 11 having its ends stitched or otherwise secured together, as shown in Figure 4, to form a band extending around the springs in a horizontal direction. Extending around the springs at right angles to the loop 11 is a second band 12 which, like the band 11, is preferably in the form of tape having selvedge edges so as to avoid ravelings which might enter between the axle and the brass. The ends of the tape forming the band 12 may be stitched or otherwise secured together at any point found convenient as, for example, at the seam 13 shown in the upper part of Figure 1. The springs 8 are positioned a sufficient distance apart to provide space for the reception of the box lug 2. The upper and lower layers of the band 12 are secured together between springs by a short row of stitching 14 to prevent the formation of outwardly projecting folds of cloth when the filler is compressed. The edges of the tape forming the band 11 are stitched to the edges of the tape forming the band 12 except at one point where an opening 15 is left for the passage of a metal strip 16 secured to the forward spring 8 and provided with a turned over portion 17 adapted to engage with one of the lugs 18 of the brass to support the filler directly below the brass, as shown in Figure 2. The forward end of the band 11 is made of sufficient length to project beyond the collar 19 in order to pro-

vide a loop 20 forming a flexible handle for the removal of the filler. By pulling the inner side of the loop, the adjacent spring 8 may be compressed until the strip 7 is moved 6 beyond the flange, after which the filler may be pulled bodily forward, the springs being compressed as they pass the flange 19 and lug 2.

In Figures 8 and 9 we have shown a modification 10 in which the flexible handle 20 is replaced by a handle 21 of rigid material, such as wire, pivoted to the forward end of the strip 7 by a hinge member 22. The normal position of the handle will be as shown in 15 full lines in Figure 8. When it is desired to remove the filler, the handle is forced into the position shown in dotted lines in this figure. The handle will act as a lever cooperating with the edge of the flange as a fulcrum to force the strip beyond the flange 20 so that the filler may be withdrawn.

In Figures 5, 6 and 7 we have shown a modification in which the form of the filler is slightly changed and in which the filler 25 is connected by a guard member for holding down the packing at the front end of the axle. In this modification curved metal plates 24 are used in place of the fiber strips 7 to contact with the bearing surface of the axle. The lower edge of each of these strips is bent around a longitudinally extending rod 25 and clamps in position both the springs 8 and the edges of a fabric envelope 26 which incloses the springs. This envelope follows the convolutions of the spring so that the filler is longitudinally fluted in 30 form. The outer turns of the springs are preferably clamped to the fabric by metal clips 27. Each of the rods 25 is provided, 35 forward of the plate 24, with an inverted U-shaped portion 28, one arm of which is encircled by a lug 29 on the plate 24. The other arm is provided with an inwardly projecting portion 30 terminating in a forwardly projecting finger piece 31. The portion 30 extends through bearings 32 formed on a 40 guard 33. The portion 30 of the rod is longer than the bearing 32 so as to follow lateral movement of the fillers relative to the guard when inserting and removing the device. Upward movement of the guard is limited 45 by contact with the finger pieces 31. Downward movement of the guard may also be limited by a stop plate 34.

In use the fillers are inserted in the journal box in the position shown in Figures 1, 2 and 7. Due to the fact that the fillers are expandable and contractible laterally, the 50 space between the box walls and the axle bearing will be completely sealed off from the brass, not only when the axle is in its central position, but when the axle moves laterally with respect to the box, as shown in Figure 2. Consequently, none of the pack-

ing can gain access to the brass to form "waste grabs".

In the form shown in Figures 5, 6 and 7, the guard 33 performs the further function of holding down the packing in front of 70 the axle to prevent its escape through the journal box lid opening. As this guard aids in holding the filler in position adjacent the brass, we have not shown this form provided with means for suspending the fillers, such as shown in the form illustrated in Figures 1 to 4. It will be understood, however, that such suspension means may be used with this form also if found desirable.

Having fully described our invention, what 80 we claim as new and desire to secure by Letters Patent of the United States is:

1. In a device of the class described, the combination of a journal box and axle, of a brass in said box and bearing on the upper 85 part of said axle, the lower part of said box forming a chamber containing oil retaining packing, and a pair of fillers positioned one at either side of the axle contacting said axle and the box wall and forming a continuous 90 partition between the packing and the brass, said fillers being compressible and expansible in a lateral direction to maintain said contact with both the axle and box in any operative position said parts may assume. 95

2. In a device of the class described, the combination of a journal box and axle, of a brass in said box and bearing on the upper 100 part of said axle, the lower part of said box forming a chamber containing oil retaining packing, and a pair of fillers positioned one at each side of the axle and extending between it and the box wall, said fillers each comprising an elastic inner member and an 105 enclosing flexible envelope.

3. In a device of the class described, the combination of a journal box and axle, of a brass in said box and bearing on the upper 110 part of said axle, the lower part of said box forming a chamber containing oil retaining packing, and a pair of fillers positioned one at each side of the axle and extending between it and the box wall, said fillers each comprising a pair of elastic inner members spaced apart to receive a box lug between 115 them and an enclosing flexible envelope.

4. A filler for journal box bearings comprising a contact member adapted to bear upon the axle, a pair of elastic inner members carried by said contact member and spaced apart to receive a box lug between them, a flexible envelope, and suspension means carried by one of said elastic members for positioning the filler in the journal box. 120

5. A filler for journal box bearings comprising a contact member adapted to bear upon the axle, an elastic inner member, an elastic envelope, and a handle for moving the end of the contact member out of alignment 125 with the axle flange when the filler is removed 130

from the box, said handle being a lever pivoted to the contact member and cooperating with the axle flange to provide a fulcrum.

6. In a device of the class described, the combination of a journal box and axle, of a brass in said box and bearing on the upper part of said axle, the lower part of said box forming a chamber containing oil retaining packing, a pair of fillers positioned one at either side of the axle between it and the box wall and separating the packing from the brass, said fillers being compressible and expansible in a lateral direction to maintain contact with both the axle and the box, and 10 a packing guard carried by said fillers and positioned in front of the end of the axle.

7. In a device of the class described, the combination of a journal box and axle, of a brass in said box and bearing on the upper 20 part of said axle, the lower part of said box forming a chamber containing oil retaining packing, a pair of fillers positioned one at either side of the axle between it and the box wall and separating the packing from the brass, said fillers being compressible and expansible in a lateral direction to maintain contact with both the axle and the box, and 25 a packing guard carried by said fillers and positioned in front of the end of the axle, said 30 packing guard having lateral movement relative to the fillers.

8. In a device of the class described, the combination of a journal box and axle, of a

brass in said box and bearing on the upper part of said axle, the lower part of said box forming a chamber containing oil retaining packing, a pair of fillers positioned one at either side of the axle between it and the box 70 wall and separating the packing from the brass, said fillers being compressible and expansible in a lateral direction to maintain contact with both the axle and the box, and a packing guard carried by said fillers and positioned in front of the end of the axle, said 75 guard having pivoted connection with the fillers to permit of limited vertical movement.

9. In a device of the class described, the combination of a journal box and axle, of a brass in said box and bearing on the upper part of said axle, the lower part of said box forming a chamber containing oil retaining packing, a pair of fillers positioned one at either side of the axle between it and the box 80 wall and separating the packing from the brass, said fillers being compressible and expansible in a lateral direction to maintain contact with both the axle and the box, and a packing guard carried by said fillers and positioned in front of the end of the axle, said 85 guard being connected to said fillers to permit lateral and limited vertical movement 90 relative thereto.
